UNITED STATES PATENT OFFICE.

JOHN TERHUNE, OF HACKENSACK, NEW JERSEY.

DESIGN FOR A FLAG.

SPECIFICATION forming part of Design No. 22,496, dated June 6, 1893.

Application filed April 8, 1893. Serial No. 469,611. Term of patent 7 years.

To all whom it may concern:

Be it known that I, JOHN TERHUNE, of Hackensack, in the county of Bergen and State of New Jersey, have invented a new and original 5 Design for a Flag, of which the following is a full, clear, and exact description.

- Reference is to be had to the accompanying drawings forming a part of this specification, in which—
- 10 Figure 1 is a side elevation of the flag showing my design; and Fig. 2 is a similar view, showing the opposite side of the flag, these two views being deemed necessary to fully illustrate my design.
  - 15 The leading features of my design, are the insignia of Ferdinand and Isabella on one side of the flag and the representations of Columbus, his caravels, and characters representing his log, on the other side of the flag. The 20 flag is a swallow-tail flag, and is the insignia

of Ferdinand and Isabella, the same consisting of a Maltese cross and crowns. On the opposite side of the flag, near the upper and inner corner, is a portrait of Columbus, while beneath this are characters representing the 25 log kept by him during his first voyage of discovery. In the upper left-hand corner of the flag is a representation of the *Pinta*, while beneath this, near the center of the flag, is the representation of the *Santa Maria*, and in the 30 lower left-hand corner is the representation of the *Nina*.

I claim—

The design for a flag, herein shown and described.

JOHN TERHUNE.
